UNITED STATES PATENT OFFICE.

JOHN HABEIN, OF KENOSHA, WISCONSIN.

CREDIT FILING SYSTEM.

1,164,344.

Specification of Letters Patent. Patented Dec. 14, 1915.

Application filed August 2, 1913. Serial No. 782,591.

To all whom it may concern:

Be it known that I, JOHN HABEIN, a citizen of the United States, and a resident of the city of Kenosha, county of Kenosha, 5 and State of Wisconsin, have invented certain new and useful Improvements in Credit Filing Systems, of which the following is a specification.

My invention relates to improvements in 10 filing systems or cases for keeping credit accounts, and has for its object the production of a system or apparatus of this character which will be of improved construction, one which will eliminate the expenditure 15 of considerable time and labor which is now employed in the keeping of books in credit accounts, and further a construction which will be durable and economical.

With these objects in view, my invention 20 consists in the combinations and arrangements of parts hereinafter described and claimed.

The invention will be best understood by reference to the accompanying drawings 25 forming a part of this specification, and in which,

Figure 1 is a side elevation partly in section of a credit filing device embodying my invention, Fig. 2 is a vertical transverse 30 section of the device, Fig. 3 is a perspective view of one of the holders of the device detached, and Fig. 4 is a perspective view of one of the partition members of the device detached.

35 The preferred form of construction as illustrated in the accompanying drawings comprises a rectangular case 1 open at its upper side. Said case is provided with a suitable hinged lid or cover 2 with which co- 40 operates a suitable lock 3 for securing the same in closed position, a slotted link 4 co-operating with said cover for supporting the same in open position.

The interior of the case 1 is divided by a 45 medial longitudinally extending partition 5 into two similar compartments, the outer or lateral walls of said compartments being lined with metallic sheets of lining 6. Provided at the upper edges of the partition 5 and lining 6 are inwardly extending flanges 7 adapted for service in the capacity hereinafter described.

Arranged in each of the compartments 55 of the case 1 is a plurality of holders each of which is adapted, when the device is in use, to support or hold the order or credit

slips or sheets of a customer carrying a credit account with the house or concern using the device. Each of said holders comprises a flat rectangular body 8 formed 60 preferably of sheet metal at the lateral edges of which are provided forwardly and inwardly turned flanges 9. At the lower edge of each of said holders is provided a forwardly projecting flange 10 from the 65 outer edge of which extends an upwardly projecting ear 10', and at the upper edge of said holder is provided a forwardly and downwardly projecting ear or retainer member 11. The arrangement is such that 70 each of the holders will be formed with a shallow recess or compartment at its front side for the reception of the order or credit slips 12, as clearly shown in the several views, the construction being such that the 75 upper portion of the top or foremost slip will be exposed to view. Also, with this arrangement, it will be seen that slips may be readily and expeditiously inserted or removed from a holder by simply buckling the 80 same in order to engage or disengage the upper edge thereof with or from the retainer member 11.

Provided at the lower edge of each of the 85 holders are laterally projecting ears 13 which serve to releasably lock the holders to the case 1 but which permit of partial removal thereof, as shown in dotted lines in Fig. 1, said ears co-operating with the flanges 7, as will be readily understood. 90 Complete release or removal of a holder may be effected by turning the same in a horizontal plane so as to position the same obliquely in the corresponding compartment of the case since by this operation the ears 95 13 will disengage the flanges 7 so as to permit of the desired detachment of the holder. The reverse operation is of course resorted to in inserting the holder in position.

Provided at the upper edge of each of the 100 holders is an extension 14 which is bent into triangular form in cross section and provided with a depressed or inwardly punched portion 15 at its upper side for supporting an index member or name card 15' as shown 105 in Fig. 2, the index member or name card when secured in position being supported upon the depressed portion 15 with the ends of said member or card projecting under the portions 14'. With this arrangement the 110 index member or name card will be positioned so as to be readily observed, thereby

facilitating the finding of any particular name when the device is in use.

The holders are separated by flexible partitions 16 formed preferably of sheet metal, each of said partitions being provided at its lower edge with an angularly disposed flange 17. Said partitions are releasably secured in position and connected together with each other by means of a slender flexible strip 18 provided at the bottom of each of the compartments of the case 1 which engages slots 19 provided at the lower ends of said partitions as clearly shown in Fig. 1. With this arrangement it will be seen, that the partitions 16 are loosely connected so as to be spaced apart any distance to suit conditions and if not in use may be removed if desired by simply sliding the same from engagement with the corresponding retaining member 18. The members 18 as well as the partitions connected therewith are loosely arranged in the case 1, the same simply resting upon the bottom of the compartments of said case, this construction being simple and economical and being adapted for ready assemblage in the manufacture of the device.

In using the device a holder will be utilized for each of the credit accounts of the user of the device, the name of the customer or debtor being arranged in the support 14 at the upper edge of the holder. The various holders are then preferably arranged alphabetically so as to render the location of any one of the same easy when the device is in use. Also, in order to further facilitate the location of the various accounts or holders, the index or name supporting members 14 of adjacent holders are preferably arranged at opposite edges or sides of the holders so that the names upon adjacent holders will alternate and thus will not cover one another. With this device each order or purchase will be noted upon an order or purchase slip 12 the amount of the purchase being totaled as shown in Fig. 2. In

each succeeding purchase or order the total upon the previous slip or order will be forwarded, as shown in Fig. 2 in a space provided therefor and so that the condition of each account will always be disclosed upon the last or foremost slip 12 arranged in the particular holder. This arrangement eliminates the use of the customary books used in book keeping with the time and labor incidental to the keeping thereof. The construction is simple and economical and hence may be manufactured at a low cost.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

A device of the class described comprising a receptacle, a plurality of holders loosely mounted within said receptacle and provided at their upper and lower edges with tongues adapted to retain material thereunder, in combination with a corresponding number of slideable partitions arranged alternately with said holders and adapted to rest against said tongues and to prevent the several holders when being moved inwardly and outwardly, from injuring the material held under the tongues of the adjacent holder, substantially as described.

In testimony whereof I have signed my name to this specification in the presence of two subscribing witnesses.

JOHN HABEIN.
